UNITED STATES PATENT OFFICE.

ROBERT T. MUSSETT, OF WATERLOO, IOWA.

STEAM BOILER.

Application filed July 25, 1927. Serial No. 208,325.

My invention relates to improvements in steam boilers, and the object of my improvement is to supply a sectional boiler adapted to efficiently function without water tubes, being consequently stronger and requiring less expense of maintenance than boilers having the latter construction, especially for relatively small installations.

This object I have accomplished by the means which are hereinafter described and claimed, and which are illustrated in the accompanying drawings, in which Fig. 1 is a longitudinal vertical section taken through a furnace and boiler of my said improved construction, showing some structures thereof in side elevation. Fig. 2 is a front end elevation thereof with parts removed, and Fig. 3 is a rear elevation thereof with parts removed. Figs. 4 and 6 are side elevations respectively of the outer and inner boiler sections, with a part of each broken away. Fig. 5 is a vertical cross section through the outer section of said Fig. 4.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

The lower part only of the furnace walls 1 is shown, the upper parts being removed in order to thereby better disclose the inner parts of the furnace and the boiler sections and other elements. To the rear of the front wall 4 is the fire-box, 9 with ash-pit below (not shown), the housing wall 1 having a clean-out door 11. The front wall has the usual superposed fire-door 7 and ash-door 8. The usual bridge 2 crosses the fire-box about medially having an upright upper baffle part 6 extending only to the tops of the boiler sections 9 and 10. The arrows in Fig. 1 indicate the course of the heated gases of combustion through the furnace to the chimney 20, around the lower end of a depending baffle member 5, and between the boiler sections 9 and 10. The outer boiler section 9 shown in Figs. 4 and 5 are rectangular with relatively narrowly spaced side walls braced by stay-bolts or headed rivets 21. On opposite ends of said sections are

the screw-plugs 22 fitting interiorly threaded seats therein. These fasten steel front and back plates over the front and rear walls of the furnace and also can be removed for clean-out purposes. The inner sections 10 are of triangular shape with their inclined walls below, sloping rearwardly. This affords a clear fire-box space in front below the diminished ends of the sections 10. 60 These sections 10 also have end screw-plugs 22 for a like use. All the boiler sections 9 and 10 have receiving nipples 14 at the lower parts of their rear walls and delivery nipples 13 projecting upwardly from the forward 70 parts of their top walls.

The housing having been removed as also top closure members for the furnace below, Fig. 1 shows the steam drum 17 as supported longitudinally above the inner boiler sections 10 and as having an end man-hole with a closure device 19, secured by clamping members 18. The lower front sides of the drum 17 has oppositely projecting legs 12 in communication with the top delivery nipples 13 of the boiler sections 9 and 10. A downwardly directed conduit 3 leads from the lower part of the rear head of the drum 17 to the middle of a transverse leg 15 positioned across the rear wall of the furnace, 80 having a number of screw-plugs 16 for cleaning-out purposes, and having opposite them the receiving nipples 14 of the sections 9 and 10 with which the leg is in communication. 85

Water heated in the forward parts of the 90 sections 9 and 10 rises through the delivery nipples 13 to the legs 12 and then passes therethrough into the drum 17. A circulation is set up through this drum and out through the pipe 3 to the lower leg 15 and 95 the receiving nipples 14 to the sections.

The boiler sections 9 and 10 have large capacity for water, which, when fully heated, tends to evenly retain heat although the furnace fire may at times diminish in its 100 intensity. This adapts the boiler for many uses, as for water heating supply. The inner sections 10, because of smaller size than the outer sections 9 and because of having both side walls of each fully exposed to the heated gases of combustion, have their water contents heated more rapidly initially and throughout there is a more rapid circulation therethrough. This hastens the heating of the water in the drum 17, while 110 conversely, the outer sections 9 with their larger water content, retard the cooling of

the water therein longer than that contained in the sections 10. An equalization is obtained thereby.

The sections 9 and 10 have much less liability to become silted up quickly than tubular boilers, and the sections are easily cleansed of sediment by way of the nipples 14 when the screw-plugs 16 are removed. The sections are also relatively inexpensive, strongly stayed, and disassembled without difficulty.

Having described my invention, what I claim as new, and desire to secure by Letters Patent, is:

15. In combination, a housing, a firebox in said housing and a plurality of laterally

spaced closed hollow boiler units supported in said fire box, the units being relatively narrow transversely, with the outer units transversely alined and rectangular, and the inner units being triangular with longitudinally inclined bottoms alined transversely, a steam dome supported longitudinally above said units, means of communication between opposite ends of said dome and the lowermost parts of the units at one end, and with the uppermost parts of the units at the opposite end respectively, said units having clean-out ports, and closures removably mounted in said ports.

In testimony whereof I affix my signature.

ROBERT T. MUSSETT.
